WINDING

Edward J. Abbott, Wilton, N. H., assignor to
 Abbott Machine Company, Wilton, N. H., a corporation of New Hampshire

Application June 1, 1940, Serial No. 338,313

15 Claims. (Cl. 242—159)

This invention relates to a wound yarn package and method of winding.

One object of the invention is to produce an improved package having a self-sustaining cross-wound end or ends but largely wound in a spool wound formation, thus attaining nearly the high density and high capacity of a cylindrical spool wound package but wound on a core from which one or both of the heads are omitted.

Further objects of invention are to improve the construction of a headless cross-wound end portion of a wound package. In particular the invention aims to avoid "cob-webbing" or failure of the cusps of yarn to lie in the desired plane at the end face and to avoid excessive flanging or unduly large diameters of the end portions as compared with the main portion of the package. These aspects of the invention are of especial importance in winding on ring spinning or twisting machines or similar machines where the traverse element is at some distance from the face of the winding package so that a sharp reversal of the yarn at the end face is ordinarily impossible, and where there is no provision for applying pressure to the package to roll or press its end portions in to the desired diameters.

Other objects of invention and features of advantage and utility will be apparent from this specification and its drawing wherein the invention is explained by way of example.

In the drawing:

Fig. 1 is a side view of the tubular core with a layer of quick traverse winding thereon;

Fig. 2 is a side view of the same tubular core with a few, for example, twenty layers of quick traverse winding thereon; and

Fig. 3 is a side view of the tubular core showing in full line the core with spool winding thereon and in dotted lines the outline of the finished package.

The package of this invention is started by first winding on the tubular core a few layers of cross winding (for example twenty) as shown in Fig. 1. This cross winding will, after a few layers have been laid, pile up at the ends of the package and there form flanges 8, 8 where the cusps of the spirals of yarn overlie.

Then a few layers of winding having a slower traverse than the initial layers of cross winding, preferably as shown in Fig. 3 consisting of spool winding, that is slow traverse winding having the coils nearly perpendicular to the axis of the package, are laid on the package. This slow traverse or spool winding has a slightly shorter length of traverse than the cross winding, and

is continued until the diameter of the package is as large in the center as it is at the ends where the flanges 8, 8 lie. (See Fig. 3.)

Next a few more turns of cross winding are laid on the package and further similar flanges are built up at the ends of the package, and then the slow traverse winding is again resumed, having a slightly shorter length of traverse than the cross winding, and this slow traverse or spool winding is again continued until the diameter of the package is as large in the center as it is at the ends. This sequence is preferably continued until the package reaches its desired diameter, which may for example be such as indicated in dotted lines in Fig. 3.

The invention permits the winding, on a machine that has no provision for rolling in the flanges that form at the end faces of the package, of an outwardly cylindrical package which is tied together endwise by cross winding and hence is self-sustaining, and which has a greater yarn capacity due to its being wound in large part with slow traverse winding.

I claim:

- 25 1. A method of preparing a textile package comprising winding the same yarn alternately in a plurality of layers of cross-winding and in a plurality of layers of winding having a slower traverse than the said layers of cross-winding, and adding further pluralities of layers of cross-winding and pluralities of layers of winding having a slower traverse than the cross-winding, said layers of cross winding and layers of slow traverse winding being superposed.
- 30 2. A method of preparing a textile package comprising winding the same yarn alternately in a plurality of layers of cross-winding and in a plurality of layers of spool winding, and adding further pluralities of layers of cross-winding and pluralities of layers of spool winding until the package is completed, said layers of cross winding and layers of spool winding being superposed.
- 35 3. A method of preparing a textile package comprising winding the same yarn alternately in a plurality of layers of cross-winding in which flanges are built up at the ends of the package, and in a plurality of layers of winding having a slower traverse than the cross-winding in the space between said flanges, and adding further pluralities of layers of cross-winding and pluralities of layers of winding having a slower traverse than the cross-winding until the package is completed.
- 40 4. A method of preparing a textile package comprising winding the same yarn alternately in

- 45
- 50
- 55
- 60
- 65

a plurality of layers of cross winding in which flanges are built up at the ends of the package, and in a plurality of layers of spool winding in the space between said flanges, and adding further pluralities of layers of cross winding and pluralities of layers of spool winding until the package is completed.

5. A method of preparing a textile package comprising winding the same yarn alternately in a plurality of layers of cross winding, in which flanges are built up at the ends of the package, and in a plurality of layers of winding having a slower traverse than the cross winding in the space between said flanges, and adding further pluralities of layers of cross winding and pluralities of layers of winding having a slower traverse than the cross winding until the package is completed, the slower traverse winding having a slightly shorter length of traverse than the cross winding.

6. A method of preparing a textile package comprising winding the same yarn alternately in a plurality of layers of cross winding, building up flanges at the ends of the package, and in a plurality of layers of spool winding in the space between said flanges, and adding further pluralities of layers of cross winding and pluralities of layers of spool winding until the package is completed, the spool winding having a slightly shorter length of traverse than the cross winding.

7. A package consisting of the same yarn wound in layers of cross winding and in layers of winding having a slower traverse than the cross winding, the layers of the slower traverse winding being interspersed between layers of cross winding.

8. A package consisting of the same yarn wound in layers of cross winding and in layers of spool winding, the layers of the spool winding being interspersed between layers of cross winding.

9. A package consisting of the same yarn wound in layers of cross winding and in layers of winding having a slower traverse than the layers of cross winding, the slower traverse winding being interspersed between layers of cross winding and having a slightly shorter length of traverse than the cross winding.

10. A package consisting of the same yarn wound in layers of cross winding and in layers of spool winding, the layers of the spool winding being interspersed between layers of cross winding and having a slightly shorter length of traverse than the cross winding.

11. A method of preparing a textile package comprising winding the same yarn alternately in a plurality of layers of cross winding in which

flanges are built up at the ends of the package, and in a plurality of layers of winding having a slower traverse than the cross winding, said layers of slower traverse winding filling up the space between the flanges formed by the cross winding, and adding further pluralities of layers of cross winding and pluralities of layers of winding having a slower traverse than the cross winding until the package is completed.

12. A method of preparing a textile package comprising winding the same yarn alternately in a plurality of layers of cross winding in which flanges are built up at the ends of the package, and in a plurality of layers of spool winding which fill up the space between the flanges formed by the cross winding, and adding further pluralities of layers of cross winding and pluralities of layers of spool winding until the package is completed.

13. A method of preparing a textile package comprising winding the same yarn alternately in a plurality of layers of cross winding in which flanges are built up at the ends of the package, and in a plurality of layers of winding having a slower traverse than the cross winding in the space between said flanges, and adding further pluralities of layers of cross winding and pluralities of layers of winding having a slower traverse than the cross winding until the package is completed, the slower traverse winding having a slightly shorter length of traverse than the cross winding and filling up the space formed by the flanges built up at the ends of the package by the layers of cross winding.

14. A method of preparing a textile package comprising winding the same yarn alternately in a plurality of layers of cross winding, building up flanges at the ends of the package, and in a plurality of layers of spool winding in the space between said flanges, and adding further pluralities of layers of cross winding and pluralities of layers of spool winding until the package is completed, the spool winding having a slightly shorter length of traverse than the cross winding and filling up the space formed by the flanges built up at the ends of the package by the layers of cross winding.

15. A package consisting of the same yarn wound in layers of cross winding, said layers of cross winding building up flanges at the ends of the package, and in layers of spool winding which fill up the space between the said flanges, the layers of spool windings being interspersed between the layers of cross winding and having a slightly shorter length of traverse than the cross winding.

EDWARD J. ABBOTT.
